UNITED STATES PATENT OFFICE

2,561,034

COMBINATION VIBRATOR AND VACUUM
MASSAGE DEVICE

Emmitt J. Phillips, Los Angeles, Calif., assignor
of one-third to Arlis F. Phillips and one-third
to Lela J. Phillips

Application March 19, 1949, Serial No. 82,345

1 Claim. (Cl. 128—32)

1
This invention relates to combination vibrator and vacuum massage device, and more particularly to the combination of a vibrating mechanism with means in combination therewith for creating a suction during the vibrating treatment and through the same device used for the vibrating.

The invention is designed to apply suction through the massaging device, so that when it is applied to the scalp and the hair, for example, dandruff will be drawn off with other matter which may be stirred up during the massaging.

Another object of the invention is to provide a vibrator device to which various massaging, brushing and treating devices can be attached and interchanged as may be necessary and convenient for the best service.

Another object of the invention is to provide a simple and practical body which can be attached to the vibrator mechanism, to be vibrated therewith, and to which various massaging, brushing and other treating members or devices can be detachably connected, and which can be connected with a source of suction or with a blower, whereby suction can be set up through said body and the treating members or devices connected therewith, or whereby a blower treatment can be put through said body, as when it is desired to dry the hair or other parts of the body.

Other objects and advantages of the invention will be apparent from the following more detailed description of one practical embodiment thereof, taken with the accompanying sheet of drawings, in which

Figure 1 is a side elevation of a vibrator of known make, with a combination vacuum body and massaging device connected therewith, ready for use, with parts in section to show the interior arrangement;

Figure 2 is a bottom plan view thereof;

Figures 3 and 4 are side views, partly in section, of two devices to be connected with the body member on the vibrator;

Figure 5 is a side elevation of a complete combination vibrator and vacuum connecting member connected therewith as a part thereof;

Figure 6 is a sectional detail on line 6—6 of Fig. 5.

Referring now in detail to the drawings, a known make of vibrator, designated 1, is shown in Fig. 1, with a vacuum body member 8 attached thereto, as at the attaching screw 9, said body having an elbow outlet at 10, threaded to receive a massaging device, designated 11, as clearly

5 shown, such massaging devices, where vacuum is used in connection therewith, having around the working face, a flexible flange 12, to engage with the face, body or scalp to make the vacuum action more effective.

In Figure 3 is a brush, designated 13, which can be connected with the body member 8, in place of the massaging device 11, for use in brushing the hair and at the same time applying the

10 suction thereto.

In Fig. 4 is another form of massaging device, of the flexible cup form, designated 14.

It will be noted that all of the various devices for attachment to the vibrating member, are 15 open in their centers for the suction to be applied during the vibratory treatment.

The electric cord to said vibrator is designated 15, and the regular switch is designated 16. The hose, designated 17, may come from a portable 20 vacuum cleaner, or such other source of suction, or air under pressure for blowing purposes, in the well-known manner. Referring to Fig. 5, I have shown a special embodiment of the invention in a complete, self-contained unit, in which 25 is embodied the vibrator mechanism, and the connection for the vacuum action is made as a part thereof. The body of this embodiment of the invention is designated 18, with the wire connection 19 for the vibrator therein, with a 30 switch 20. An upstanding rib or lug portion 21 has a hole 22 therein, by means of which the device can be hung upon a hook, if desired. Secured to the under side of said body is a tubular member 23, of rectangular form in cross section, 35 except at its outer end 24, which is provided with a connection 25 for the hose 26, as shown. The other end of said member is provided with the elbow connection 27, to which the various massaging and body treating members can be connected, as before described. Said tubular member 40 is shown secured by means of a screw bolt 28, although this could be made integral with the body, if desired.

45 Thus I have provided an improved combination of body vibrator and suction for the effective treating of the human body, and particularly the scalp and hair, where, in addition to massaging the head and the scalp, suction can be applied for carrying off dandruff and other loose matter which may be worked out by the massaging and vibrating action.

I do not, however, limit the invention to the details of construction and arrangement shown 50 for explanatory purposes, except as I may be

limited by a fair interpretation of the hereto appended claim.

I claim:

A combination vibrator and suction device, including as a unitary mechanism, a vibrator to be held in the hand of the operator, a tubular member secured directly to the underside of said vibrator, said tubular member having means for attaching a hose thereto at one end, and at its other end having an elbow thereon directed downwardly therefrom and adapted to have detachably secured thereto a massaging member of open construction, to permit suction there-

through from said tubular member to which it is secured.

EMMITT J. PHILLIPS.
